6431X William Lawrence - New Haven, Connecticut.

Third Patent

(Patented March 23, 1831. Reissued March 10, 1834.)

The Invention referred to in these Letters Patent and making part of the same, containing a description in the words of the said William Lawrence himself of his improvement in the Chandelier or Hanging Lamp, for which Letters Patent were granted dated the 23rd day of March, 1831, (which Letters Patent being hereby cancelled in favour of a defective Specification.)

To all to whom these presents shall come. I Bid it known that I William Lawrence of New Haven in the County of New Haven and State of Connecticut have invented or now and am perfecting an improvement in the Chandelier or hanging lamp that on the twenty third day of March in the year of one thousand one thousand and eight hundred and thirty one, and of the Independence of the United States of America the fifty fifth I obtained Letters Patent of the said United States in due form for said invention or improvement, signed by Andrew Jackson President of the United States, and with the seal of the United States thereto affixed. And finding the specification of the said invention or improvement, made by me and annexed to said Letters Patent to be defective and inaccurate, I have surrendered the said Letters Patent and caused the same to be created in the Department of State of the United States, and now for the purpose of claiming Letters Patent for said invention or improvement for the unexpired part of the fourteen years since obtaining the first Patent, I hereby declare that the following is a full and exact description of the said Chandelier or hanging Lamp as mounted or improved by me. The principal object of my improvement is to cause a more perfect and equal diffusion of clear and white light as well under as above and around the lamp. This is effected by an opening through the body of the Lamp or vessel containing the oil, of such form and relation to the location of the works as not materially to intercept the radiations of light and by a separate number of works placed in tubes inserted in the upper part of the lamp and by a glass tube placed at a proper height above the upper extremity of the body of the lamp. By this combination

MOW 23, 1831

light is transmitted in direct rays to every commanding point, and the air by radiation is made to pass especially over each side of the vessel, which is close contact with the flame so as to consume the smoke and render the light white clear and vivid. Although this lamp may be made in forms somewhat different, yet the best manner of constructing it is the following. — First. — Let the body of the lamp itself, consist of two shells, nearly concentric made of British iron, the proper inside, each resembling an inverted bowl with an opening about three inches, in the bottom more or less, according to the size of the lamp, the one placed ~~over~~ the other with the edges united. This union however on the top of the lamp should be by a flat surface of about three-fourths of an inch in width, with a header sawed edge on its sides to prevent the oil from running over and thereby keeping the body of the lamp clean. Let the inner shell be in the form of the inverted frustrum of a cone, diverging when suspended about forty or forty-five degrees from a line perpendicular to the horizon. Let the outer shell be worked between the upper and lower edges so as to leave sufficient space for from three gills to a pint of oil, or a greater or less quantity according to the size of the lamp. The tube or feeder to be placed at or near the top of the lamp. The lamp above described should be about seven inches in diameter. Secondly. — Let there be two or more flat tubes made of tin or other suitable material about one inch wide and about four inches in length inserted into the space between the shells, through the flat surface above described standing at about the same inclination as the inner shell, and extending about three-fourths of an inch out of the lamp, with slits through one side of them to insert a few other pointed instrument in order to raise or depress the work to a suitable elevation. — These tubes may but be made a little conical so as to come just when inserted with the circular form of the lamp, and may be either fixed or so applied as to be drawn out, elevated or depressed at pleasure. — Thirdly. — On or near the flat surface aboveshown on the top of the lamp, set three small pillars or standards of brass or other proper metal on which place a globular glass tube

in common form and as aforesaid to receive the same about one half or three fourths of an inch above the top of the lamp. On the pillars make a notch or shoulder on which the glass tube may rest. Secure the tube in the common way by a small screw passing through the top of one of the pillars and packing against the glass. The outer edge thereof being turned a little out in the usual form.

Fourthly. Let the scrolls or hooks be fixed to the outer and lower edge of the lamp to receive the chains by which it is suspended in the usual way of suspending a lamp (which may be still more convenient) these hooks may be fixed to a narrow metallic band so formed as to cut the lower edge of the lamp into it. That it may be removed without removing the chains either from the hooks, or the place of suspension. when this lamp is suspended in a cotton, factory or other situation particularly exposed to fire. a plane glass may be placed in the band or other wise under the lamp so as to prevent the danger. the edge of this glass must rest on small knobs, or be a little uneven so as to permit the passage of air upwards — A reflector although less necessary than in common lamps may be affixed above the lamp in the usual form and may be made of tin or other polished metal. or of glass, mirror — I do not claim as my invention the tubes for the wicks, nor the glass tube with an opening through the body of the lamp simply. But what I do claim as my invention or improvement is the following combination (No. 1). The lamp with an opening through the body thereof in such form in relation to the wicks as not materially to intercept the radiation of light emitted with the tubes for the wicks. and with a glass tube placed at a proper distance above the body of such a lamp. so as to cause such a current of air on each side of the wicks as to produce a white dry and vivid light and effect a consumption of the wicks. Dated at Meudon this first day of March A.D. 1831.
